UNITED STATES PATENT OFFICE.

HERBERT E. MERSELES AND HENRY R. MERSELES, OF BRONXVILLE, AND CHARLES F. SIMMONS, OF NEW ROCHELLE, AND PAUL H. ENGEL, OF NEW YORK, N. Y.; SAID HENRY R. MERSELES, SAID SIMMONS, AND SAID ENGEL ASSIGNS TO SAID HERBERT E. MERSELES.

WASHING MACHINE.

Application filed May 5, 1921. Serial No. 467,046.

To all whom it may concern:

Be it known that we, HERBERT E. MERSELES, HENRY R. MERSELES, CHARLES F. SIMMONS, and PAUL H. ENGEL, citizens of the United States, residing, respectively, at Bronxville, county of Westchester, and State of New York; Bronxville, county of Westchester, and State of New York; New Rochelle, county of Westchester, and State of New York; and New York city, county of Bronx, and State of New York, have invented certain new and useful Improvements in Washing Machines, fully described and represented in the following specification and the accompanying drawings, forming a part of the same.

This invention relates to washing machines and has for an object to provide a small, simple and compact mechanism which will adequately clean dishes and other articles.

Dish washing machines heretofore used have customarily included a comparatively large tank or similar receptacle and various different moving parts secured to different parts of the tank or the framework supporting the tank so that it has been necessary to provide a special tank which formed a part of the machine and to attach various different parts of the working mechanism in different related positions upon the tank and its framework in order to assemble the machine.

The present invention provides a complete device including the dish washing mechanism for directing water against the dishes and mechanism for actuating the dish washing mechanism all mounted compactly upon a single rigid frame. The actuating mechanism of the device is automotive, that is, it does not require a mechanical connection to an outside driving means. This device we have termed a dish washing unit.

A dish washing unit made in accordance with the invention may be completely assembled with all its parts in proper operative relation and thereafter applied to any desired form of receptacle, such as a tank, sink, or basin. In the form which we consider most desirable, the frame of the dish washing unit includes a part which is adapted to form a closure for an opening in the bottom of the receptacle to which the unit is applied. It is thus possible to apply

the completely assembled unit to any receptacle provided with a suitable opening in its bottom by merely placing the unit in this opening and securing it to the bottom of the receptacle about the edge of the opening.

In order that the invention may clearly be understood, we will describe in detail the specific embodiments of it which are illustrated in the accompanying drawings, in which:

Fig. 1 is a side elevation partly in section of a complete dish washing machine incorporating the dish washing unit;

Fig. 2 is a horizontal section on the line 2—2 of Fig. 1;

Fig. 3 is an enlarged vertical section of the lower portion of the dish washing machine of Fig. 1 showing the construction of the dish washing unit;

Fig. 4 is a horizontal section on the line 4—4 of Fig. 3 showing the construction of the pump;

Fig. 5 is an elevation partly in section showing the application of the dish washing unit to a well provided at the side of a sink and below the drain board of the sink;

Fig. 6 is a perspective view showing a removable attachment for sinks incorporating the dish washing unit;

Fig. 7 is an elevation partly in section showing the application of the dish washing unit to a sink; and

Fig. 8 is a plan view of the arrangement shown in Fig. 7 with the part of the dish washing mechanism above the bottom of the sink removed.

The dish washing machine shown in Figs. 1 to 4 comprises a tank 10 which may be constructed of sheet metal or other suitable material. The tank 10 is supported upon legs 11. The inner surface of the tank 10 is provided with an inwardly projecting bead 12, or other suitable means, for supporting the rack 13 in which the dishes or other articles to be washed are placed. The bottom 14 of the tank 10 is preferably downwardly inclined towards its center as shown in Fig. 3. At the center of the bottom 14 is a circular opening 15.

The dish washing unit 20 is inserted in the opening 15 and secured to the bottom of the tank about the periphery of the opening, no other support for it being necessary. As hereinafter explained, the frame of the unit

is formed to provide a closure for the opening 15 so that it serves to complete the bottom of the tank 10.

The non-rotary part or frame 21 of the 5 dish washing unit 20 is rigid and provides the stationary part of the dish washing mechanism and of means for actuating the dish washing mechanism and includes supporting bearings for the rotary portions of 10 the dish washing mechanism and actuating mechanism. In the form illustrated, the stationary part of the dish washing mechanism comprises a pump body 22. The upper part of the pump body 22 forms a casing 15 23 providing a chamber for a rotary impeller while the bottom 24 of the pump body 22 is spaced from the casing 23 and forms a closure for the opening 15 in the bottom of the tank 10. Three radial fins 25 connect the 20 casing 23 of the pump body with the bottom 24 of the body. The space between the fins 25 and between the bottom 24 and the lower wall 23' of the casing 23 forms inlet 25 passages communicating with the tank 10 and leading from the side of the pump body to points near the middle of the pump body. These inlet passages have wide, low openings at their outer ends and their cross-section gradually decreases toward their inner ends. 30 From the center of the top of the casing 23 projects a neck 26 forming an upwardly directed discharge opening. The motor casing 30 is rigidly secured to the lower side of the bottom 24 of the pump body 22. In 35 the form illustrated, the motor casing is provided with three upwardly extending arms 31, which are preferably made integral with the upper part of the casing 30. The outer ends of the arms 31 are connected by 40 a ring 32 preferably made integral with the arms, and this ring is secured by screws 33 to the bottom 24 of the pump body 22. The top or upper end of the motor casing 30 is imperforate except for the shaft opening at 45 its center.

In the rigid frame 21 of the unit is rotatably mounted a vertical shaft 40 which is common to the motor and the pump of the washing mechanism. The shaft 40 is supported upon a thrust bearing 41 located in a boss 46 projecting downward from the lower end of the motor casing 30. A shoulder 42 on the shaft 40 forms the upper race 43 of the bearing, while the lower race 44 of 50 the bearing is formed by the upper end of a threaded sleeve 45 which is screwed into the bottom 24 of the pump body 22. It is apparent that the arrangement described affords means for the vertical adjustment of the shaft 40. A bearing 55 47 is provided for the shaft 40 in a boss 48 projecting from the upper end of the motor casing 30. The shaft 40 extends upwardly from this bearing into the pump body 22 through a centrally located hole 50 in the bottom 24 of the pump body. The upper

portion of the hole 50 may form an additional bearing 51 for the shaft 40 and the lower portion of this hole is of larger diameter than the shaft, affording space for a stuffing box 52. The packing 53 of the stuffing 70 box 52 is compressed by a threaded sleeve 54 screwed into the lower portion of the hole 50.

A deflecting flange 55 is mounted upon the shaft 40 just above the top of the boss 48 of the motor casing 30. This flange serves to 75 direct any water which may leak through the stuffing box 52 outwardly from the shaft so that it falls upon the imperforate top of the motor casing 30 and is thus prevented from entering the motor. 80

An impeller 60 is fixedly mounted upon the upper end of the shaft 40 within the chamber provided by the casing 23. From the upper end of the hub 61 of the impeller 60 extends a disc-shaped flange 62 from 85 which depend spiral blades 63 preferably made integral with the flange. Similar fixed spiral blades 64 are secured to the top of the casing 23 above the disc-shaped flange 62 and are preferably cast integrally with the 90 top of the casing. A clearance is provided between the bottom of the impeller hub 61 and the bottom 24 of the pump body 22 so that the vertical position of the impeller 60 in the chamber provided by the casing 23 95 may be accurately adjusted by means of the threaded sleeve 45 at the bottom of the motor casing 30. The impeller is so adjusted that the top of its flange 62 just clears the lower edge of the fixed blades 64 while the 100 lower edge of the impeller blades 63 just clears the lower wall 23' of the casing 23. The threaded sleeve 45 is also used to take up for wear upon the thrust bearing 41 so as to prevent such wear from causing the 105 shaft 40 to drop sufficiently to bring the impeller blades 63 into contact with the lower wall 23' of the casing 23.

A bushing 70 is removably secured in the discharge opening formed by the neck 26 110 of the pump body 22, by a screw 71 which passes through a tapped hole in the side of the neck 26 and enters an annular recess 72 in the bushing 70. A hollow hub 73 is rotatably mounted in the bushing 70. The hub 115 73 is provided at its lower end with an external flange 74 which engages under the lower end of the bushing 70 and thus prevents the hub from moving upwardly in the bushing. Hollow spray arms 75 and 76 extend radially from the hollow hub 73 above the top of the neck 26. The spray arms 75, 76 are provided along their upper sides with upwardly directed discharge orifices 77, 78, 79, 80 and 81. One or more of the discharge 120 orifices are inclined so that the reaction of water discharged through them causes a rotation of the hub 73 and arms 75, 76. In the form shown in the drawings, the two discharge orifices 78, 81 at the ends of the arms 125

130

are thus inclined. It should be noted that the distance of the discharge orifice 77 of the arm 75 from the axis of the hub 73 is greater than the distance of the discharge orifice 79 of the arm 76 from the axis and less than the distance of the orifice 80 from the axis. Consequently, when the arms rotate, the orifice 77 moves in a circle between the circles in which the orifices 79 and 80 move. If desired, the end orifices 78, 81 may be located at different distances from the axis of the hub so as to rotate in different circles. Although in the apparatus illustrated the spray arms 75, 76 are formed of pieces of metal separate from the hub 73, this is not essential, and the use of the word "hub" and the word "arms" in the claims should not be understood to imply that the hub is necessarily separate from the arms, for it may be merely the axial portion of an integral member which forms both the arms and the hub.

The rigid frame 21 of the unit is formed to provide an annular external flange which in the form illustrated consists of a flat ring 85 secured to a flange 86 surrounding the bottom 24 of the pump body and to the ring 32 of a motor casing by bolts 87. After the dish washing unit as described has been completely assembled it is placed in the opening 15 from above and secured in position by attaching the flange 85 to the bottom of the tank about the periphery of the opening 15 by soldering, bolting or otherwise. If desired, the ring 85 may be secured to the bottom of the tank before it is attached to the frame 21 of the unit. In this case the ring 85 becomes in effect a portion of the bottom of the tank to which the frame of the unit is attached by bolting the flange 86 to the ring 85. In either case after the unit has been secured in position the portion 24 of the frame 21 of the unit forms a closure for the opening in the bottom of the tank.

The closure 24 is provided with an eccentric opening 90 which serves as a drain opening for the tank and may also be used for filling the tank. In the form shown in Fig. 3 the opening 90 is connected by an elbow pipe 91 through a three-way valve 92 with a pipe 93 leading from a source of hot water and a pipe 94 leading to a drain.

In the tank 10 above the intake openings 55 of the pump body 22 and below the spray arms 75, 76 is placed a screen or strainer 95. The screen 95 preferably consists of two semi-circular portions as indicated in Fig. 2 which may be removed from the tank when the spray arms 75, 76 occupy a position at right angles to that shown in Fig. 2.

In using the dish washing machine described, a rack 13 containing soiled dishes or other articles to be washed is placed in 65 the tank 10 upon the bead 12. Hot water is admitted to the tank through the opening 90 by placing this opening in communication with the supply pipe 93 through the three-way valve 92. Sufficient water is admitted to submerge the inlet openings between the fins 25 of the pump body. The valve 92 is closed before the water reaches the level of the arms 75, 76 and preferably when the water is a little below the screen 95. Soap or washing powder is then preferably added to the water in the tank. The motor is then operated, rotating the vertical shaft 40. This rotates the impeller 60 which is mounted upon the shaft 40. The impeller blades 63 draw water from the tank through the inlet passages between the fins 25 and throw it outwardly in the casing 23, while giving it a whirling motion. Owing to the form of the inlet passages air is not drawn into the pump even when the water in the tank is so shallow that it just submerges the outer ends of these passages. The stationary blades 64 direct the water whirling about in the casing 23 to the center of the casing whence it is discharged upwardly through the neck 26 into the hub 73. It passes through the hub into the spray arms 75, 76 and out through the upwardly directed discharge orifices 77, 78, 79, 80, and 81 of the spray arms in fan-shaped sprays. The reaction of the water discharged through the inclined orifices 78, 81 causes the hub and arms to rotate. In this rotation the discharge orifices 77, 79 and 80 move in different circles so that water is projected upwardly against all parts of the dishes contained in the rack 13, serving thoroughly to cleanse them in a very short time. During this operation, the solid matter removed from the dishes is caught upon the screen 95 and thus prevented from entering the pump casing. Upon the completion of the washing, the water in the tank is withdrawn through the opening 90 by placing this opening in communication with the drain pipe 94 through the three-way valve 92. Clean water may then be admitted as before from the pipe 93 and the operation repeated to rinse the dishes and remove all soapy water from them.

The dish washing machine shown in Figs. 1 to 4, which has been described, illustrates the application of the new automotive dish washing unit to a tank designed to be used for dish washing only. While the compactness of the dish washing unit and the fact that it may be completely assembled before being applied to the tank makes the dish washing machine described simpler and more economical to manufacture than dish washing machines heretofore made, the utility of this compact dish washing unit is still more evident in connection with the application of it to other types of receptacles.

In Fig. 5 is shown a kitchen sink 100 130

which is divided by an integral partition 101 into a shallow portion 102 and a deep portion 103. The deep portion 103 has at its bottom an opening 15' about the periphery of which the dish washing unit 20 is secured. The cover 104 of the deep portion 103 of the sink serves as a drain board for the shallow portion 102 of the sink. As sinks are customarily provided at 10 one side with such a drain board, the location of the dish washing unit under the drain board places it out of the way and in a space which would otherwise not be used. In the form shown in Fig. 5, the opening in 15 the portion of the frame of the unit which forms a closure for the opening 15' in the bottom of the deep portion 103 in the sink is connected through a three-way valve 92 to the drain pipe 105 of the shallow portion 20 102 of the sink and to the pipe 106 which supplies the hot water faucet 107 above the shallow portion 102 of the sink. If desired, however, the opening in the frame of the unit may be connected only to the drain and 25 water may be introduced into the deep portion 103 of the sink through an aperture in the partition 101 which may be provided with a removable closure.

Fig. 6 shows the dish washing unit 20 applied to a cylindrical tank 10' the upper edge of which is secured about the periphery of an opening in a board 120, preferably made of sheet metal, so that the tank is suspended from the board. The board 120 is 30 provided with legs 122 and is adapted to be placed at the side of a kitchen sink 121. The inner end of the board 120 rests upon the edge of the sink 121 and is supported thereby while the outer end of the board is 35 supported by the legs 122. The cylindrical tank 10' is in general similar to the tank 10 shown in Fig. 1 and the washing unit 20 is mounted in its bottom in the same way. A drain board 123 is hinged to the board 120. 40 This drain board dish washing attachment occupies but a small space and may be applied to any sink without alteration thereof, it being merely necessary to make the pipe connections between the dish washing unit 45 and the drain pipe and hot water pipe of the sink. The washing unit below the drain board is in convenient position for use whenever desired, it being merely necessary to raise the drain board 123 to obtain access to 50 it. When the washing mechanism is not in use the drain board 123 lies upon the board 120 covering the tank 10', and is in position to serve as a drain board for the sink 121.

Figs. 7 and 8 show another application of 60 the dish washing unit 20 to a kitchen sink. In this form, the sink 109 is of the usual size and shape except that it is provided at the center of its bottom with a circular well 110 at the bottom of which is an opening 15". 65 It is about the periphery of this opening that

the frame 21 of the dish washing unit 20 is secured. The depth of the well 110 is such that while the entire pump body 22 is below the bottom of the sink 109, the arms 75, 76 are above the bottom of the sink 109. The 70 dish rack 13' is provided with legs 111 which are seated upon the bottom of the sink 109 and serve to hold the rack above the arms 75, 76. A removable dome-shaped cover 112 which may be either square or circular in 75 cross-section is placed over the dish rack and arms to confine the water projected upwardly from the arms. The bottom of the sink 109 may be provided with a rib 114 to position the legs of the rack and the cover. The 80 screen 95 is at the level of the bottom of the sink 109. The drain opening in the unit frame may be connected to the drain pipe of the sink through a valve 113. It is not necessary to connect this opening with a source 85 of hot water as the well 110 may be filled with hot water from the hot water faucet 115 of the sink. This is done before the cover 112 is placed in position.

When it is desired to use the sink 109 independently of the dish washing unit, the cover 112 and the rack 13' are removed from the sink. The screen 95 may then be removed so that the screw 71 may be reached and loosened, permitting the withdrawal of 90 the bushing 70 from the discharge neck 26 so that the arms, hub and bearing may be lifted out. The screen 95 is then replaced and a plug or cap 116 placed in the discharge neck 26 (Fig. 8). When this has been done no 100 portion of the washing mechanism remains within the sink 109 so that the sink may be used in the ordinary manner.

The combined sink and dish washing apparatus shown in Figs. 5 to 8 forms the subject matter of our divisional application filed January 19, 1924, Serial No. 687,180, and is, therefore, not claimed herein. Furthermore, certain features illustrated and described in this application and independent of the invention claimed herein constitute a part of the subject matter of the co-pending application of one of us, Herbert E. Merselles, as co-inventor with Frank W. Bemm, filed October 9, 1919, Serial No. 329,- 110 533, and are, therefore, not claimed herein. 115

It should be understood that the dish washing unit described may be applied to other types of receptacles than those illustrated. Furthermore, the invention in its broadest sense is not limited to the particular embodiment of it illustrated since the unit may be constructed so as to embody washing mechanism of various different types. We believe that the invention has 125 produced the first compact self-contained dish washing unit comprising both dish washing mechanism and actuating mechanism, and we wish it understood that it is our intention to claim such a unit and the 130

mechanical features which make possible the construction of such a unit, independently of the particular type of washing mechanism or actuating mechanism which may be incorporated in the unit.

What is claimed is:

1. In combination with a receptacle having an opening in its bottom, a dish washing unit including dish washing mechanism and automotive actuating mechanism therefor, and comprising a rotary member including a part of the dish washing mechanism and a part of the actuating mechanism and a single rigid shaft on which both 10 said parts are mounted, and a single rigid non-rotary frame formed to provide supporting bearings for said rotary member and to provide a closure for the opening in the receptacle.
2. A dish washing unit as claimed in claim 1, in which the portion of the rigid frame forming a closure for the opening in the receptacle contains a drain opening for the receptacle so that no other drain 25 for the receptacle need be provided.
3. A dish washing machine, comprising the combination with a receptacle having an opening in its bottom, of a rigid frame including a flat plate containing a hole and 30 having its peripheral portion secured to the bottom of the receptacle about the periphery of the opening therein so as to form a closure for said opening and a part depending from and supported by said 35 closure plate, a motor in the depending part of said frame having a vertical shaft extending into the receptacle through the hole in the closure plate, and rotary dish washing mechanism located in the receptacle 40 and actuated by said shaft.
4. A dish washing machine, comprising a receptacle having an opening in its bottom, a dish-support in said receptacle and spaced upwardly from the bottom thereof, 45 and a dish washing unit comprising a rigid frame having a part forming a closure for the opening in the bottom of the receptacle and secured to the bottom of the receptacle about the periphery of said opening and a 50 part depending from and supported by said closure, a motor in the depending part of said frame having a vertical shaft extending into the receptacle through said closure, and rotary mechanism in the lower part of 55 the receptacle actuated by said shaft and adapted to direct a washing medium upwardly against articles on the dish-support.
5. A dish washing machine, comprising a receptacle, an external support for the 60 receptacle, a support in the upper part of said receptacle for the dishes to be washed, and a dish washing unit comprising a rigid frame depending from the bottom of the receptacle and independent of the receptacle 65 and a motor in said frame below the
- receptacle having a vertical shaft extending through the bottom of the receptacle, rotary mechanism in the lower part of the receptacle actuated by said shaft and adapted to project a washing medium upwardly against 70 the dishes on said support, and means to prevent the washing medium in the receptacle from entering said motor.
6. A dish washing machine, comprising a receptacle, an external support for the receptacle, a support in the upper part of said receptacle for the dishes to be washed, and a dish washing unit comprising a rigid frame depending from the bottom of the receptacle and independent of the receptacle 75 support, a motor in said frame below the receptacle having a vertical shaft extending through the bottom of the receptacle, rotary mechanism in the lower part of the receptacle coaxial with said shaft and actuated thereby and adapted to project a washing medium upwardly against the dishes on said support, and means to prevent the washing medium in the receptacle 80 from entering said motor.
7. In combination with a receptacle having an opening in its bottom, a dish washing unit comprising a pump body forming a closure for said opening and provided 85 with inlet openings communicating with the receptacle, an upwardly directed discharge opening located within the receptacle and a central bottom opening; a motor rigidly secured to the bottom of said pump body and having a vertical shaft extending into said 90 body through its bottom opening; an impeller mounted on said motor shaft within said pump body and adapted to draw water from said receptacle through said intake 95 openings and discharge the water through said discharge opening; and means communicating with said discharge opening and adapted to direct the water discharged upwardly against dishes or other articles 100 placed in the receptacle.
8. In combination with a receptacle having an opening in its bottom, a dish washing unit comprising a pump body having an impeller-enclosing casing within said receptacle and a spaced bottom forming a closure for said opening in the receptacle, said body being provided with an intake opening between said casing and bottom, an upwardly directed discharge opening formed in said 115 casing, and a central opening formed in said bottom; a motor rigidly secured to the bottom of said body and having a vertical shaft extending through the opening in the bottom of the pump body into said casing; an impeller mounted on said motor shaft within said casing and adapted to draw water from said tank through said intake opening and discharge the water through said discharge opening; and means communicating 120 with said discharge opening and adapted to 125
- 130

- direct the water discharged upwardly against dishes or other articles placed in the receptacle.
9. In combination with a receptacle having an opening in its bottom, a dish washing unit comprising a pump body forming a closure for said opening and provided with an intake opening communicating with the receptacle, an upwardly directed discharge opening located within the receptacle and a central bottom opening; a hollow hub rotatably mounted on the pump body and having an intake opening communicating with said discharge opening; hollow spray arms extending radially from said hollow hub above said opening and having upwardly directed inclined discharge nozzles; a motor rigidly secured to the bottom of the pump body and having a vertical shaft extending into said body through the bottom opening thereof; and an impeller mounted on said shaft within said body and adapted to draw water from the receptacle through said intake opening and to force it through said hub and arms causing a rotation thereof.
10. In combination with a receptacle having an opening in its bottom, a dish washing unit comprising a pump body forming a chamber for an impeller and a closure for said opening and provided with an intake opening communicating with the receptacle at the bottom thereof, an upwardly directed discharge opening, a central bottom opening, and an eccentric bottom opening; means communicating with said eccentric opening for withdrawing liquid from the receptacle therethrough; a motor rigidly secured to the bottom of the pump having a vertical shaft extending through the central opening in said closure into said impeller chamber; a rotary impeller mounted on said shaft within the impeller chamber of the pump body and adapted to draw water from the receptacle through said intake opening and discharge it through said upwardly directed opening; and means communicating with said opening adapted to direct the water upwardly against articles placed in the receptacle.
11. In combination with a receptacle having an opening in its bottom, a dish washing unit comprising a pump body forming a closure for said opening and provided with inlet openings communicating with a receptacle, an upwardly directed discharge opening in the receptacle and a central bottom opening; a motor rigidly secured to the bottom of said pump body having a vertical shaft extending into the pump body through its bottom opening, an impeller mounted on said motor shaft within said pump body and adapted to draw water from said receptacle through said intake opening and discharge the water through said discharge opening, and a vertically adjustable thrust bearing for said shaft in said motor casing adapted to adjust the position of the impeller in the pump body.
12. A dish washing unit comprising a pump casing having an intake opening and an upwardly directed discharge opening, a hollow hub rotatably mounted on said casing and having an intake opening communicating with said discharge opening, horizontal spray arms extending radially from said hub above said opening and having upwardly directed inclined discharge orifices, a motor rigidly secured to the bottom of said casing and having a vertical shaft extending into said casing, and an impeller mounted on said shaft within the casing and adapted to draw water through said intake opening and to force the water through the hub and arms, causing a rotation thereof.
13. A dish washing unit comprising a pump casing having an intake opening, and a central upwardly directed discharge opening in its top, a hollow hub rotatably mounted on said casing and having an intake opening communicating with said discharge opening, hollow spray arms extending radially from said hub above said opening and provided with upwardly directed inclined discharge orifices, a motor rigidly secured to the bottom of said casing having a vertical shaft coaxial with said hollow hub and extending into the casing, and an impeller mounted on said shaft within the casing and adapted to draw water through said intake opening and to force the water through the hub and arms, causing a rotation thereof.
14. Dish washing mechanism, comprising a pump casing having a vertical shaft opening and an intake opening and an upwardly directed discharge opening, a hollow hub rotatably mounted on said casing and having an intake opening communicating with said discharge opening, hollow spray arms extending radially from said hub above said opening and provided with upwardly directed inclined discharge orifices, a rotary vertical shaft projecting into said casing through said shaft opening, and a rotary impeller in said casing, mounted on said shaft, and adapted to draw water through said intake opening and to force the water through said hub and arms, causing a rotation thereof.
15. Dish washing mechanism, comprising a pump casing having an intake opening and a central upwardly directed discharge opening, a hollow hub rotatably mounted on said casing and having an intake opening communicating with said discharge opening, hollow spray arms extending radially from said hub above said opening and provided with upwardly directed inclined discharge orifices, and a rotary impeller in said casing coaxial with said hub and adapted to draw water through said intake opening.

opening and to force the water through said hub and arms, causing a rotation thereof.

16. Dish washing mechanism, comprising
5 a pump casing having lateral intake openings and passages leading from said openings to the bottom of the casing near its center and having an upwardly directed discharge opening in the center of its top;
10 a hollow hub rotatably mounted on said casing and having an intake opening communicating with said discharge opening; spray arms extending radially from said hub and having upwardly directed inclined discharge orifices; a rotary impeller in said casing, coaxial with said hub, and adapted to draw water through said intake openings and passages and to throw said water to the side of the casing while giving it a
15 whirling motion; and fixed spiral blades in the casing above the impeller adapted to direct the water whirling about the side of the casing into said hollow hub so that the water is forced through the spray arms,
20 causing the hub and arms to rotate.
25

17. In a washing machine, the combination of a hollow rotatably mounted hub, two hollow spray arms extending radially from said hub, one of said arms being provided with two spaced discharge orifices, the portion of said arm between said orifices being closed, and the other of said arms being provided with a discharge orifice located at a distance from the axis of the

hub substantially equal to the distance from 35 the axis of the hub to the middle of the closed portion of the other arm between its said orifices, means for forcing water into said arms through the hub, and means for causing a rotation of the arms and hub 40 moving the discharge orifices of said first-mentioned arm in circles spaced at substantially equal distances within and without the circle in which the orifice of said second-mentioned arm is moved. 45

18. In a washing machine, the combination of a rotatably mounted hollow hub having an axial intake opening, and a pair of diametrically opposite radial arms extending from said hub, said arms being 50 provided with more than two discharge orifices positioned at such distances from the axis of the hub that each orifice moves in a different one of a set of equally spaced concentric circles when the arms rotate, 55 some of said discharge orifices being formed in one of said arms, and the remainder of them in the other of said arms.

In testimony whereof we have hereunto set our hands in the presence of two sub- 60 scribing witnesses.

HERBERT E. MERSELES.
HENRY R. MERSELES.
CHARLES F. SIMMONS.
PAUL H. ENGEL.
